Des. 217,404
Patented Apr. 28, 1970

217,404

COOKWARE DISPLAY RACK OR SIMILAR ARTICLE

Elmer L. Reibold, Park Ridge, William W. Timpe, Prospect Heights, Spartaco Trivellini, Roselle, and Kasimer F. Panek, Broadview, Ill., assignors to Market Masters, Inc., Elk Grove Village, Ill., a corporation of Illinois

Filed Mar. 26, 1969, Ser. No. 16,442

Term of patent 14 years

Int. Cl. D6—01

U.S. Cl. D80—10

FIG. 1

FIG.2

FIG.3

FIG.4

FIG. 1 is a perspective view of a cookware display rack embodying our new design;

FIG. 2 is a reduced top plan view thereof;

FIG. 3 is a reduced front elevational view thereof; and FIG. 4 is a reduced side elevational view thereof.

We claim:

The ornamental design for a cookware display rack or similar article, substantially as shown.
